UNITED STATES PATENT OFFICE

172,475

ASH TRAY

Edward F. McDonald, Buffalo, and James V. Vevirit, Kenmore, N. Y., assignors to McDonald Products Corporation, Buffalo, N. Y., a corporation of New York

Application February 13, 1953, Serial No. 23,606

Term of patent 14 years

(Cl. D85—2)

To all whom it may concern:

Be it known that we, Edward F. McDonald and James V. Vevirit, citizens of the United States, residing at Buffalo, New York, and Kenmore 17, New York, respectively, have invented a new, original, and ornamental Design for an Ash Tray, of which the following is a specification, reference being had to the accompanying drawing, forming a part hereof.

Fig. 1 is a perspective view of an ash tray, showing our new design;

Fig. 2 is a top plan view thereof; and

Fig. 3 is a side elevational view thereof.

We claim:

The ornamental design for an ash tray, as shown.
